MILLING MACHINE

Fred A. Hassman, Cincinnati, Ohio, assignor to
The Cincinnati Milling Machine Company,
Cincinnati, Ohio, a corporation of Ohio

Application January 25, 1930. Serial No. 423,523

3 Claims. (Cl. 90—14)

This invention relates to milling machines and more particularly to a device for counterbalancing the spindle heads on vertical type machines.

One of the principal objects of this invention is the provision of an improved counterweight for vertical milling machines, that will occupy a smaller amount of space and thus be adapted to fit in the gooseneck portion of the column. It has been common practice to provide counterweights for vertical spindle heads of milling machines but these counterweights are usually suspended in the vertical part of the column. In prior machines this was feasible, as the interior of the column was not used for any purpose except perhaps for a single transmission line to rotate the spindle. In accordance with more recent developments, however, the space in the column has been taken up, such as the installation of change boxes of one type or another, and it has been necessary to provide a new and improved type of counterweight which will occupy less space without loss of efficiency.

Another object of this invention is the provision of an improved counterbalancing mechanism adapted to be directly connected to the spindle head.

Other objects and advantages of the present invention should be readily apparent by reference to the following specification, considered in conjunction with the accompanying drawings illustrative of one embodiment thereof, but it will be understood that any modifications may be made in the specific structural details hereinafter described, within the scope of the appended claims, without departing from or exceeding the spirit of the invention.

Referring to the drawings, in which like reference numerals indicate like parts:

Figure 1 is a plan view of the end of a gooseneck column;

Figure 2 is a vertical section on the line 2—2 of Figure 1;

Figure 3 is a section on the line 3—3 of Figure 1;

Figure 4 is a section on the line 4—4 of Figure 1; and

Figure 5 is a diagrammatic view showing the location of the counterweights in the old style machines.

The reference numeral 10 indicates the overhanging portion of a gooseneck column having vertical guideways 11, in which is slidably mounted the spindle head 12 which carries the rotatable spindle 13. Spindle 13 has a bevel gear 14 splined thereto which is driven by the bevel gear 15 at-

tached to the end of the horizontal shaft 16. The shaft 16 may be driven by a prime mover in any suitable manner. It will be noted from Figure 1 that the shaft 16 is centrally mounted in the column.

The spindle head has attached to its rear portion the rack 17 which is operatively engaged by the gear 18 mounted on the end of the stub shaft 19 journaled in the column and having the handle 20 on the outer end thereof. The rack 17 has directly connected thereto, by means of the pin 21 and the chain 22, the counterweight 23. The chain 22 passes over the sprocket 23', which is pinned to the shaft 24 journaled in the upper part of the column. On the other end of the shaft 24 is another sprocket wheel 25, keyed thereto, over which passes the chain 26 having one end attached to the sprocket wheel as by the bolt 27 and the other end attached to the counterweight 28. The chains 22 and 26 are attached to the weights by means of the bolt 29 passing through the center of the weight and having a nut and washer on the lower end thereof.

It will be noted that the counterbalance for the spindle head has been divided into two weights. This is necessary for two reasons, first, to prevent interference with the shaft 16 which passes through the center part of the column and, second, in order to make the weights shorter and confine them in a smaller space. It will be noted from Figure 5, which shows the old construction, that the length of the weight was immaterial. Attention is also called to the fact that the chain 22 is connected direct to the head, although it could be wound up on the shaft 19. It is preferred, however, to connect it direct to the head, as it relieves the teeth of the rack and gear of the strain of being under constant tension. An opening 30 is provided in the top of the column for the convenient insertion of the weights into the column.

What is claimed is:

1. A milling machine having a column with a laterally curved upper portion forming an overhanging chamber having parallel side walls, said walls terminating in parallel vertical guides, a spindle carrier slidably mounted on said guides having a cutter spindle journaled therein, a horizontal drive shaft extending centrally through said chamber dividing the same into a plurality of compartments, the depth of said chamber being less than the range of movement necessary for a single counterweight for the spindle carrier, means operatively coupling the shaft to the spindle, means to effect vertical ad-

justment of the carrier including a shaft journaled in one of the side walls, means operatively connecting the shaft to the head whereby rotation thereof will effect vertical adjustment of the spindle carrier, means to counterbalance the carrier comprising a cross shaft journaled in the side wall at right angles to the drive shaft, a plurality of counterbalancing weights suspended from said shaft, one being mounted in each of said compartments the sum of said weights approximating the weight of said carrier, and means connecting the cross shaft to said head whereby upon adjustment of the head all of said weights will coact to counterbalance the head.

15. 2. In a milling machine having a column with a projecting, over-hanging portion, said portion forming an inclosed chamber, the combination of a spindle head mounted on said portion for vertical movement, a cutter spindle journaled in said head, power actuated means for rotating said spindle, and means self-contained within said chamber for counterbalancing the spindle head, the depth of said chamber being less than the range of movement necessary for a single counterweight for the spindle carrier comprising a shaft journaled transversely of the chamber and in the upper part thereof, sprocket wheels mounted on each end of the shaft, a first weight, supporting means for the weight passing over

and attached to one sprocket wheel, a second weight, supporting means therefor passing over the other sprocket wheel and attached to said head, and mechanism for effecting vertical movement of the spindle head whereby movement of one weight by the head will automatically cause movement of the other weight, the sum of said weights approximating the weight of said head.

3. A milling machine comprising a column, an overhanging portion projecting from the column and forming an inclosed chamber, guideways formed on the free end of said portion, a spindle carrier slidably mounted in said guideways, a cutter spindle journaled in said carrier, a power shaft rotatably mounted centrally of said chamber for rotating the spindle, said shaft dividing the chamber into two portions, the depth of said chamber being less than the range of movement necessary for a single counterweight for the spindle carrier, means to counterbalance the carrier comprising a pair of weights suspended on opposite sides of said shaft, means operatively connecting one of said weights to the head for joint movement therewith, means operatively connecting the remaining weight to the first weight for actuation thereby, and manually operable rack and gear means for effecting adjustment of the carrier.
